T. T. SCOTT.
FURNACE TAPPING MACHINE.
APPLICATION FILED MAY 19, 1920.

1,361,103.

Patented Dec. 7, 1920.

UNITED STATES PATENT OFFICE.

THOMAS T. SCOTT, OF YOUNGSTOWN, OHIO.

FURNACE-TAPPING MACHINE.

1,361,103.

Specification of Letters Patent. Patented Dec. 7, 1920.

Application filed May 19, 1920. Serial No. 382,487.

To all whom it may concern:

Be it known that I, THOMAS T. SCOTT, a citizen of the United States, residing at Youngstown, in the county of Mahoning and State of Ohio, have invented certain new and useful Improvements in Furnace-Tapping Machines; and I do hereby declare the following to be a full, clear, and exact description of the invention, such as will enable others skilled in the art to which it appertains to make and use the same.

This invention relates to new and useful improvements in furnace tapping machines and has for its primary object the provision 15 of a device of the above stated character which will take the place of an ordinary jib crane now used in connection with furnaces and which will open and close the tap hole of said furnace.

Another object of this invention is the provision of a carriage carrying a tool actuating device and which may be moved 20 toward and from the furnace as desired.

A further object of this invention is the provision of means whereby the tool operating device may be raised and lowered so that the same may be positioned to open 25 and clean the tap hole and then elevate it to permit the molten metal to flow freely 30 from the furnace.

A further object of this invention is the provision of a furnace tapping machine of the above stated character, which will be simple, durable and efficient, and which may 35 be manufactured and sold at a comparatively low cost.

With these and other objects in view as will become more apparent as the description proceeds, the invention consists in the 40 certain novel features of construction, combination, and arrangement of parts as will be hereinafter more fully described and claimed.

For a complete understanding of my invention, reference is to be had to the following description and accompanying drawings, in which:—

Figure 1 is a sectional view, illustrating a furnace tapping machine constructed in 50 accordance with my invention,

Fig. 2 is a horizontal sectional view illustrating the carriage and hoisting means,

Fig. 3 is a vertical sectional view illustrating the carriage and the tool holder,

Fig. 4 is a detail view illustrating the means for locking the tool holder at adjusted positions.

Referring in detail to the drawings, the numeral 1 indicates a furnace that has the usual tap hole 2 for permitting molten metal 60 to be discharged from said furnace when open and said tap hole is adapted to be closed with the usual filling material. The foregoing description relates to a furnace of an ordinary type and with which my invention is associated.

A supporting beam 3 extends along the furnace adjacent its upper end and is supported in any desired manner and has suspended therefrom a turn table 4 to which is 70 connected supporting arms 5. The supporting arms 5 are attached to a track 6 including rack rails 7 to support a carriage 8. The carriage 8 consists of a rectangular frame 9 in which are journaled axles 10 75 having secured to their ends pinions 11 which mesh with the rack rails 7. The axles 10 have mounted thereon gears 12 connected by an endless chain 13 and said chain also has in engagement therewith a driving 80 pinion 14 secured to the armature shaft of an electric motor 15 of a well known reversible type. The electric motor 15 being of the reversible type permits the carriage 8 to be moved toward and from the furnace. 85

The carriage 8 has secured thereto a platform 16 provided with an opening to slidably receive a rack bar 17 which depends downwardly from the carriage and carries at its lower end a tool operating means 18. 90 Guide rollers 19 are journaled to the platform 16 and engage the rack bar 17 and one of said guide rollers has a series of teeth formed thereon adapted to mesh with the teeth of the rack bar 17 and forms a gear 95 20'. A driving gear 20 is in mesh with the rack bar and is secured to the armature shaft of an electric motor 21 carried by the carriage 8 and which is of the ordinary reversible type, therefore it will be seen that 100

the motor 21 is capable of raising and lowering the rack bar 17 and the tool actuating means 18 for the purpose of moving said tool actuating means into and out of alignment with the tap hole 2 of the furnace. The gear 20' has formed thereon a ratchet 22 which is adapted to be engaged by a pivoted and spring actuated dog 24 having secured to one end a cable or flexible element 10 25 so that said dog may be moved out of engagement with the teeth of the ratchet 22 permitting the tool actuating means 18 to be lowered by setting the motor 21 in operation in one direction or if the tool actuating means 18 is of sufficient weight the same will move down by gravity. It is also to be noted that the teeth are so arranged on the ratchet gear 22 that the rack bar is free to be moved upwardly on rotation of the motor 21 in one direction but will be prevented from moving downwardly by the dog 24.

The tool operating means 18 consist of a housing 25 which has journaled therein a tool operating shaft 26 that has connection 25 with an electric motor 27 secured to said housing while the other end of said shaft 26 is provided with the usual chuck 28 to receive ordinary tapping tools employed for removing the material from the tap hole 2 30 of the furnace. The housing 25 in rear of the chuck 28 is provided with an outlet opening 29 and an inclined deflecting partition 30 is located in the housing to cause the material forced into the housing from the tap hole by a boring operation to pass outwardly of the said housing by the outlet opening 29.

The tool actuating means 18 is lowered until it is in alignment with the tap hole 40 and a drill or boring tool is secured in the chuck and the carriage 8 is moved forwardly on the track 6 by the motor 15 until the tool is within the tap hole and the motor 27 is set in operation to render a rotating or boring action to the drill or auger which will remove a portion of the material from the tap hole which is of a soft nature. The material within the tap hole at the outer portion of said hole is rather soft, while said 50 material at the inner end of the hole becomes extremely hard from excessive heat of the furnace. After the soft material has been removed from the tap hole, a drill is placed within the chuck and the carriage 8 is racked back and forward on the track 6 to cause a drilling action on the hard material within the inner end of the tap hole, so that said hard material will be driven into the furnace permitting the molten metal 55 therein to escape through the tap hole. When the tap hole has been opened, the motor 15 is reversed moving the tool actuating means 18 rearwardly and the motor 21 is then set in operation to elevate said tool

actuating means out of the path of the flow- 65 ing metal from the tap hole.

A hoisting carriage 31 is mounted on the track 6 and is provided with a hoisting drum 32 on which is wound a hoisting cable 33 so that a runner spout or other articles or 70 devices associated with the furnace may be raised and lowered by setting the hoisting drum in rotation by a suitable means (not shown).

While I have shown and described the 75 preferred embodiment of my invention, it will be understood that minor changes in construction, combination, and arrangement of parts may be made without departing from the spirit and scope of the invention 80 as claimed.

Having thus described my invention, what I claim is:—

1. A device of the character set forth comprising a supporting beam, a turn table suspended from the supporting beam, a track carried by the turn table, a carriage mounted on said track, means for reciprocating said carriage, a rack bar carried by said carriage, means for raising and lowering 90 the rack bar, and a tool actuating means carried by said rack bar.

2. A device of the character set forth comprising a supporting beam arranged adjacent a furnace, a turn table movably suspended from said supporting beam, a track carried by said turn table, a carriage mounted on said track, means for reciprocating said carriage, a rack bar slidably mounted on said carriage and depending downwardly 100 therefrom, means for raising and lowering the rack bar, and a tool actuating means carried by the lower end of the rack bar.

3. A device of the character set forth comprising a supporting beam, a turn table 105 connected to the supporting beam, a track carried by the turn table, a carriage reciprocally mounted on said track, a rack bar slidably mounted in said carriage, means for raising and lowering the rack bar and carried by the carriage, a housing secured to the lower end of the rack bar, a motor carried by said housing, a shaft journaled in said housing and connected to the motor and adapted to have tools connected thereto, 115 said housing having an outlet opening therein, and a deflecting blade within said housing and adapted to cause material to pass outwardly of said opening.

4. A device of the character set forth 120 comprising a supporting beam, a turn table carried by said supporting beam, a track carried by said turn table, a carriage reciprocally mounted on said track, a tool actuating means adjustably carried by said carriage, and a hoisting means carried by said track.

5. A device of the character set forth

comprising a supporting beam, a turn table carried by the supporting beam, rack rails carried by the turn table, a carriage mounted on the rack rails, a reversible electric motor 5 for driving the carriage in either direction, a rack bar slidably connected to the carriage, a motor for raising and lowering the rack bar and carried by the carriage, means for locking the rack bar in adjusted posi-

tions, and a tool actuating means carried by 10 the rack bar.

In testimony whereof I affix my signature in presence of two witnesses.

THOMAS T. SCOTT.
